UNITED STATES PATENT OFFICE.

SIMON A. JAROSLAWSKI-FIORET, OF NEW YORK, N. Y., ASSIGNOR TO FIORET, INC.,
OF NEW YORK, N. Y., A CORPORATION OF NEW YORK.

VANITY CASE.

Application filed January 8, 1925. Serial No. 1,255.

To all whom it may concern:

Be it known that I, SIMON A. JAROSLAWSKI-FIORET, a citizen of Poland, and a resident of the city of New York, borough of 5 Manhattan, in the county and State of New York, have invented a new and Improved Vanity Case, of which the following is a full, clear, and exact description.

This invention relates to vanity cases, an 10 object of the invention being to provide a neat and attractive case which may contain either loose powder or compact, and which will function with equal facility when used either with powder or compact.

15 A further object is to provide a vanity case having an improved construction of body in which a receptacle is removably held in place by a hinged ring, the latter adapted to contain a perforated disk which may be removed as occasion may require.

20 A further object is to provide a vanity case, which can be manufactured and sold at a reasonably low price, which will be small and compact, and which will most efficiently 25 perform the functions for which it is intended.

With these and other objects in view, the invention consists in certain novel features 30 of construction and combinations and arrangements of parts which will be more fully hereinafter described and pointed out in the claims.

In the accompanying drawings—

Figure 1 is a plan view showing my improved vanity case with the cover moved to 35 open position;

Figure 2 is a view in section on an enlarged scale on the line 2—2 of Figure 1;

Figure 3 is a view in section on an enlarged scale on the line 3—3 of Figure 1, the 40 perforated plate being omitted and a compact shown in the receptacle.

1 represents the body of my improved vanity case, and 2 the cover therefor which 45 is hingedly connected at one edge as shown at 3 and is adapted to be held in closed position by means of any suitable catch 4. The cover 3 preferably contains a mirror 5 which is accessible for use when the cover is opened.

50 The body 1 has its lower portion or bottom 6 of general concavo-convex shape. Externally the bottom is convex, and in this bottom a pan or receptacle 7 is located and has a concavo-convex bottom conforming in

shape to the bottom 6 so as to rest snugly 55 and smoothly thereon.

In the upper portion of the body 1 a normally fixed ring 8 is mounted. This ring 8 is preferably stamped from suitable material, and while it is normally fixed it is 60 capable of being removed from the casing.

As a convenient means of holding the ring in the casing I have shown the ring as provided with outwardly stamped tongues 9 which engage under the shoulders 10 on the 65 body portion 1, although other means for holding the ring 8 may, of course, be employed.

Within this ring 8 a movable or hinged ring 11 is provided. This ring 11 is connected to the ring 8 by means of a hinge 12 and is provided at a point opposite the hinge 12 with a U-shaped spring catch 13 adapted to be projected through a slot 14 in ring 8 to hold the ring 11 in closed position. 70

75 The pan or receptacle 7 above referred to is of a diameter to snugly fit within a depending flange 15 on ring 8, and the ring 11 is of angular form in cross section so that its depending flange 16 engages the inside of 80 the pan or receptacle 7 and holds the latter firmly in place.

This pan or receptacle 7 may contain 85 loose powder, as indicated by the reference numeral 17, and in such case I provide a perforated cover plate 18 over the pan or receptacle. This plate 18 is formed with any desired number of perforated depressions 19, and the edge of the plate is bent inwardly and then downwardly, forming 90 an annular flange 20 which fits snugly within the ring 11. When the device contains loose powder, the powder may find outlet through the perforations 19 by shaking or otherwise manipulating the vanity case. 95

As in Figure 3, the plate 18 may be removed and a compact 21 located in the pan or receptacle 7 and held therein by engagement of the ring 11 with the compact.

It will thus be noted that with my improved vanity case either loose powder or compact may be employed, and in either case the device will function equally well. 100

The parts are so constructed and arranged as to be readily movable or removable and 105 a convenience of assemblage is had.

Various slight changes and alterations might be made in the general form of the

parts described without departing from the invention, and hence I do not limit myself to the precise details set forth but consider myself at liberty to make such slight changes and alterations as fairly fall within the spirit and scope of the appended claims.

I claim:

1. A vanity case, comprising a body, a ring fitting the body and forming a portion 10 of the top thereof, a second ring hinged to the first-named ring, means for holding the hinged ring in closed position, a receptacle in the body having its upper edge located between the two rings, and a cover for the 15 receptacle.
2. A vanity case, comprising a body, a ring fitting the body and forming a portion of the top thereof, a second ring hinged to the first-named ring, means for holding the 20 hinged ring in closed position, a receptacle in the body having its upper edge located between the two rings, a cover for the receptacle, the bottom, of said body being outwardly curved, and a mirror in said cover.

3. A vanity case, including a body and a 25 cover therefor, a ring normally fixed in the body and having a depending flange at its inner edge, a ring hinged to the first-mentioned ring and having a depending flange, a receptacle in the body secured between 30 said depending flanges, and a perforated removable plate having a depending flange fitting within the hinged ring.

4. A vanity case including a body and a 35 cover therefor, a ring normally fixed in the body and having a depending flange at its inner edge, a ring hinged to the first-mentioned ring and having a depending flange, a receptacle in the body secured between 40 said depending flanges, a perforated removable plate having a depending flange fitting within the hinged ring, an opening in the fixed ring, and a U-shaped spring catch on the hinged ring adapted to engage in the opening and hold the parts in normal 45 position.

SIMON A. JAROSLAWSKI-FIORET.
